UNITED STATES PATENT OFFICE.

WILLIAM W. SMITH, OF HAWTHORNE, CALIFORNIA.

ELECTRIC REGULATOR FOR INCUBATORS.

1,189,400.

Specification of Letters Patent.

Patented July 4, 1916.

Application filed March 9, 1915. Serial No. 13,273.

To all whom it may concern:

Be it known that I, WILLIAM W. SMITH, a citizen of the United States, residing at Hawthorne, in the county of Los Angeles and State of California, have invented certain new and useful Improvements in Electric Regulators for Incubators, of which the following is a specification.

This invention relates to apparatus for controlling the action of hot air currents and has special reference to the electric thermostatic control of incubators and the like.

In the hatching of poultry it is especially important that the temperature to which the eggs are subjected, be kept below a predetermined maximum temperature, slight drops below the minimum temperature not being so great an importance. It is also important that, when the maximum desirable temperature has been exceeded, the eggs be cooled to the minimum.

The principal object of the present invention is to provide an improved apparatus having novel arrangements for preventing heating to too great a temperature above a desired maximum and for cooling the device to the minimum desired upon reaching the upper temperature limit.

Another object of the invention is to improve and simplify the general construction of apparatus of this character.

With the above and other objects in view, as will be hereinafter set forth, the invention consists in general of certain novel features of construction and combinations of parts hereinafter fully described, illustrated in the accompanying drawings and specifically claimed.

In the accompanying drawings; Figure 1 represents the general layout of an apparatus constructed in accordance with this invention; and Fig. 2 is an enlarged detail of certain contacts.

In the embodiment of the invention hereinafter disclosed, and which represents merely one form of such invention, there is shown an incubator casing 10 provided at the bottom with the usual air inlet 11 and at the top with the air outlet 12 controlled by a damper 13. In the casing 10 is a heating drum 14 which communicates at one end with a chimney 15 and has a connection 16 at its other end leading to a heater chimney 17 open at its top, the open end being controlled by a damper 18. Extending into the lower end of the chimney 17 is the chimney 19 of a

lamp 20. By this arrangement, if the damper 18 is closed the hot products of combustion will all pass through the drum 14 while, if the damper 18 be open the hot products of combustion will pass out of the top of the chimney 17. In like manner, if the damper 13 be closed the heated air will be held in the casing 10, while, if said damper 13 be open, the heated air will pass freely from the casing.

Fixed within the casing 10 is a bracket 21 whereon is mounted an adjustable thermostat 22, preferably of the expansible type. Pivoted on the bracket 21 is a lever 23 having operative connection with the thermostat as shown at 24. The free end of this lever is provided with contact points 25 arranged for selective engagement with the adjustable contact screws 26 and 27, these being respectively termed the maximum and minimum contact screws.

At 28 and 29 are located magnets, known as the maximum and minimum magnets respectively. These magnets are connected in multiple to the battery 30 by connections 31, this battery being connected to the lever 23 by a wire 32.

At 33 and 34 are contact screws pertaining to the respective magnets 28 and 29 and connected by wires 35 and 36 to the screws 26 and 27.

The dampers 13 and 18 are carried by levers 37 and 38, pivoted at 37' and 38', and which are connected by a link 39 and from the lever 38 depends a rod 40 which is connected to the free end of a lever 41 pivoted at 41' and carrying an armature 42 for the magnet 28. This lever 41 also carries a latch arm 43 engageable, when the lever is depressed by energization of the magnet 28, with a latch 44 formed on one arm 45 of a bell crank, the arm 46 of which carries an armature 47 for the magnet 29, the two arms being secured to an insulating block 45' suitably pivoted to a support, not shown. The arms 45 and 46 carry respective spring contacts 48 and 49 engageable with the contact screws 33 and 34 according as the bell crank lever moves to one position or the other, it being understood that the weight of the armature 47 and the weight of the arm 46 combine to move the bell crank in one direction while the magnet 29, when energized, moves the bell crank in the opposite direction. The bell crank is connected to the magnets, as at 50.

In operation, when the temperature in the casing 10 rises to the desired maximum, say 103° F., a circuit is closed through contact 26 which energizes magnet 28. This draws 5 down the lever 41 and opens the dampers to permit escape of hot air from the casing 10 and hot products of combustion from the top of the chimney. At the same time the latch 44 locks the lever 41 in depressed position by engagement with the latch arm 43. The temperature in the casing then falls and when the minimum has been reached a circuit is closed through the contact 27 which energizes the magnet 29 and releases the 10 latch from the latch arm, whereupon the dampers close by gravity and the temperature again rises in the casing 10. The temperature is thus kept within desired limits.

There has thus been provided a simple and 20 efficient device of the kind described and for the purpose specified.

It is obvious that many minor changes may be made in the form and construction of the invention without departing from the 25 material principles thereof. It is not, therefore, desired to confine the invention to the exact form herein shown and described but it is wished to include all such as come within the scope claimed.

Having thus described the invention, what 30 is claimed, is:—

In combination, a thermostat, a lever actuated thereby, a battery, a connection be-

tween the lever and one pole of the battery, a pair of contact points arranged on 35 opposite sides of the lever and arranged to be selectively engaged thereby, a pair of magnets connected to the remaining pole of the battery, a pair of dampers, a pair of pivoted levers each of which carries one of 40 the dampers, a damper-controlling lever operatively connected to the free ends of the levers to move the same in unison, and provided with an armature controlled by one of the magnets, a bell crank lever provided 45 with an armature controlled by the remaining magnet, contact points adjacent the arms of the bell crank lever and arranged to be selectively engaged by the respective arms upon change of position of said bell crank 50 lever, electrical connections between said first and second contact points, electrical connections between said magnets and bell crank lever, a latch arm carried by the damper-controlling lever, and a latch on the bell 55 crank lever engageable with the latch arm upon energization of one magnet and disengageable therefrom upon energization of the other magnet.

In testimony whereof I affix my signature 60 in presence of two witnesses.

WILLIAM W. SMITH.
